BY

INVENTOR:

William Wilson

ATTORNEYS.

UNITED STATES PATENT OFFICE.

WILLIAM WILSON, OF SELMA, ALABAMA.

MACHINE FOR STEAMING HATS.

Application filed October 6, 1921. Serial No. 505,742.

To all whom it may concern:

Be it known that I, WILLIAM WILSON, a citizen of the United States, and a resident of Selma, in the county of Dallas and State 5 of Alabama, have invented certain new and useful Improvements in Machines for Steaming Hats, of which the following is a full, clear, and exact description, reference being had to the accompanying drawings, 10 forming part of this specification.

My invention relates to machines for steaming the crowns and brims of hats, and it has for its object to furnish a machine with which all kinds and shapes of hats of 15 any material can be conveniently and effectively steamed, all wrinkles removed and the sizing of the hat both for crown and brim set and hardened and the hat turned out in perfect condition in a small fraction 20 of the time now required and with great uniformity and ease of operation.

While many machines have been designed for the pressing and molding of hats, the methods employed in the steaming of hats 25 have been, to a large extent, hand-work consisting of covering the hat with a dampened cloth and then applying heated hand-irons to drive steam into the hat and obtain the necessary pressure to block the hat. Necess- 30 sarily this operation is slow and tedious, lacks uniformity and covers only a portion of the hat at a time. Instead of applying the heat and pressure by hot irons, sand bags heated by steam are also employed 35 with, possibly, greater uniformity of operation and less liability of omitting a portion of the hat, but with little saving of time and labor.

One of the important features of my in- 40 vention consists in providing a hollow bell of a size to accommodate all shapes and sizes of blocks and forms whether of stand- 45 ard or special make, in which the steam can be distributed uniformly and instantane- ously to all parts of the hat crown and also to the brim by the control of suitable and convenient valves.

Another feature of my improvements 50 consists in the construction of a specially designed band block with which the leather

sweatband of the hat may be protected from the direct application of the steam.

These features of improvement and other details of advantage will be more particularly pointed out and claimed in the course 55 of the description that follows.

In the drawings,

Figure 1 is a side elevation of my im- 60 proved machine.

Figure 2 is a front elevation of the same 65 with the flange block and stand removed.

Figure 3 is a cross section through the main standard.

Figure 4 is an enlarged vertical section of 70 the steaming bell.

Figure 5 is a similar section of the flange 75 block and band block.

The machine is mounted on a suitable standard or support 1 provided with a broad base 2, and the standard is preferably a 80 hollow tube. At its upper end the standard supports a bell-shaped structure which is riveted or otherwise secured thereto.

This bell structure comprises an outer 85 cast or stamped metal shell 3 and an inner spun or stamped metal shell 4. The outer shell is solid while the inner shell is pro- 90 vided with a large number of small holes 5. Both inner and outer shells have outwardly curved flanges 6, 7, and they are united 95 together with a machined joint at 8. The hollow flanged portion of the bell is sepa- 100 rated from the main portion by a partition or inner rib 9 which makes a machined joint at 10 with the inner shell. The two parts of the hollow bell are further held apart and braced by the bolt and nut 11.

Steam is supplied to these two compartments through the steam supply pipe 12, which, for convenience and protection of 90 the operator, passes up through the tubular standard 1 and connects through branch 13 with a coil of pipe 14, preferably of two coils, which is mounted in the upper com- 95 partment of the bell. Another branch 15 from this steam supply pipe supplies steam to preferably a single coil 16 mounted in the flange compartment of the bell. Both of these coils of pipe are plugged at their outer 100 ends and both coils are provided with holes

16^a along their respective lengths for the delivery of steam into their respective steam chambers, as desired.

The steam supplied to the coils is regulated and controlled by valves 17, 18, which are operated by handles 19, 19^a, extending out through the bell.

Mounted to slide vertically on suitable vertical guides 20, 20, in the standard 1 is a table 21, which is coupled by connecting bars 22 with a foot treadle 23, so that the latter can be readily raised and lowered by the operator.

On this table is mounted a stand 24 adapted to support an annular form or block 25, of any desired size for the hat under treatment. These blocks are formed with a curved, upper surface 26 of the conformation of the brim of the hat and are known as flange blocks and are of various standard sizes. To support the inside of the hat, when the brim is under treatment, I also provide what is known as a band block 27, which blocks are also made of standard sizes, and for the crown of the hat, when it is treated, a crown block 28 to fit inside the hat is furnished. These hat blocks for crown, band blocks, flange blocks and flange stands are all of standard sizes for the various sizes of hats, or special sizes can be furnished. The machine, however, does not require blocks or forms specially for its use. The object is to facilitate the use of standard equipment which is found in every hat shop.

With the band blocks heretofore in use finger holes are usually provided which allow steam to enter the inside of the crown of the hat which is, of course, detrimental, 40 moreover no provision is made with the ordinary band blocks to take care of the sweatband, and to prevent the steam from direct action on the band. I have in this connection made valuable improvements in the 45 band block construction, as illustrated in the drawings.

The band block is made of some suitable non-corrosive metal composition, a solid plate 30, light and thin as compatible with 50 the necessary strength and with a circular boss 31 for a hand hold instead of the usual finger openings. The plate is provided with the annular flange 32 to cover the sweatband and an annular lip 33 is formed around the 55 periphery of the block of a size to receive the sweatband. These lips are formed of various sizes depending on whether a simple sweatband is to be protected or sweatbands with reeds. In the drawings (Figure 5) I 60 have shown the band block broken away, and on one side, the lip for a reed sweatband, and on the other, the lip for a simple band. Of course, it will not be understood that the same hat has both bands.

65 With my machine, as above described, hats

can be steamed and handled with great rapidity and uniformity, and results can be obtained in shaping, sizing and fitting of hats, which are difficult or impossible to attain by the devices and methods now in use. 70

I will readily accommodate all standard shapes and sizes of blocks and forms now in use and also special blocks and forms.

In operation the hat is placed on the hat block for crowns of the size required, drawn down and tied with hat cord; it is then placed in position in the bell either by raising the table or held by hand. The operator then manipulates the valve handle 19 admitting steam to the coil 14, which fills 80 the steam chamber and enters uniformly through the perforations in the inner shell, softening uniformly the entire crown of the hat. The form with the hat is then removed, the wrinkles pressed out 85 and the process repeated until the hat is perfectly fitted to the crown block. The hat is then removed from the block and the brim fitted over the proper sized flange block, the band block inserted, the assembly placed in 90 the flange stand and the table raised by depressing the foot treadle, bringing the hat into position with the brim pressed against the bell flange. The operator then opens the steam valve 18 admitting steam to coil 16 95 and thence the steam is driven directly against the brim, so that one steaming is usually sufficient for the brim.

Having thus described my invention, what I claim as new and desire to secure by Letters Patent, is:—

1. In an apparatus of the character described, the combination with a suitable support, of a steaming bell mounted thereon of a size to receive freely the crown of a hat, 105 the bell comprising an imperforate outer shell and an inner shell perforated throughout and spaced apart to form a steam chamber with perforated steam pipe coiled therein, and a steam supply pipe connected therewith with valve to control the same, whereby steam may be uniformly distributed in the interior of the bell.

2. In an apparatus of the character described, the combination with a suitable support, of a steaming bell mounted thereon of a size to receive freely the crown of a hat, the bell comprising an imperforate outer shell and an inner shell perforated throughout and spaced apart to form a steam chamber with an imperforate partition dividing the steam chamber into a crown and a brim section, separate perforated steam pipes coiled in said sections with a common steam supply pipe for both coils and separate 125 valves for said coils, whereby steam may be distributed uniformly to either section.

3. In an apparatus of the character described, the combination with an annular flange block and a vertically movable table 130

upon which same is mounted, of a steaming bell of a size to receive freely the crown of a hat, the bell with a hollow, curved flange to conform to the flange block, with a perforated coil of steam pipe within said flanged portion, and with the surface adjacent the block perforated uniformly throughout whereby the brims of hats may be subjected to the direct action of steam.

4. In an apparatus of the character described, the combination with an annular flange block and a vertically movable table upon which same is mounted, of a steaming bell of a size to receive freely the crown of a hat, the bell with a hollow, curved flange to conform to the flange block, with a perforated coil of steam pipe within said flanged portion, and with the surface adjacent the block perforated uniformly throughout, whereby the brims of hats may be subjected to the direct action of steam,

5. In an apparatus of the character de- 25 scribed, the combination with an annular flange block and a vertically movable table upon which same is mounted, of a steaming bell of a size to receive freely the crown of a hat, the bell with a hollow, curved flange to 30 conform to the flange block, with a perforated coil of steam pipe within said flanged portion, and with the surface adjacent the block perforated uniformly throughout, 35 whereby the brims of hats may be subjected to the direct action of steam, and a band block provided with a peripheral lip to protect the sweatband from contact with the live steam.

5. In an apparatus of the character de- 25 scribed, the combination with an annular flange block and a vertically movable table upon which same is mounted, of a steaming bell of a size to receive freely the crown of a hat, the bell with a hollow, curved flange to 30 conform to the flange block, with a perforated coil of steam pipe within said flanged portion, and with the surface adjacent the block perforated uniformly throughout, 35 whereby the brims of hats may be subjected to the direct action of steam, and a band block provided with a peripheral lip to protect the sweatband from contact with the live steam, said band block being imperforate and having a boss to serve as a hand hold in 40 inserting the block.

WILLIAM WILSON.
